GASIFYING CARBURETOR

Joseph E. Farrell, Island Heights, N. J., assignor
to Farspan Industries, Inc., Island Heights,
N. J., a corporation of New Jersey

Application April 9, 1951, Serial No. 220,026

6 Claims. (Cl. 123—133)

1

This invention relates to carburetors, and more particularly to an improvement in carburetors of the type which supply a dry gas to the intake manifold as distinguished from a carburetor which supplies a wet vapor for the combustible fuel mixture.

A primary object is to provide an assembly which includes an electrically heated starting generator for cracking of low grade fuel oils into a dry gas suitable for forming a gaseous mixture to start the operation of a motor, and a main generator heated by hot exhaust gases for sustained operation. The starting generator is preferably closely associated with the intake pipe and the main generator is preferably associated in convenient assembly with the exhaust line thereby to provide a complete gasifying unit which may be readily mounted on the motor block. While the present invention is particularly useful for stationary engines, isolated electric plants, pumping units or the like, nevertheless, these applications are stated by way of description and not by way of limitation.

Another object is to provide appropriate means for controlling the gas volume from the main generator to the gas chamber of the starting unit which communicates with the intake line to assure smooth operation of the motor, and also to provide suitable valves for controlling liquid fuel to both the main and starting generators.

A further object is to provide a main generator wherein the hot exhaust gases pass through the center thereof to completely surround a spirally wound fuel inlet coil located therein, said generator being also housed in a casing in the exhaust line so that the hot exhaust gases therein will heat the sides and ends thereof to assure complete gasification of the raw fuel before it is conveyed to the intake manifold.

A still further object is to provide the main generator with a monoxide breather tube opening into the exhaust line to serve the dual functions of: reducing the effect of total engine induced vacuum on the generator to a measured predetermined degree; and also permits oxygen lacking carbon monoxide gas into the generator to supply gas volume to the same extent as air would if admitted to the generator, but which is not used to avoid carbon deposits in the generator or gas chambers.

With the above and other objects in view which will more readily appear as the nature of invention is better understood the same consists in the novel construction, combination, and arrangement of parts, hereinafter more fully described, illustrated and claimed.

2

A preferred and practical embodiment of the invention is shown in the accompanying drawing in which:

The figure is a vertical cross section view of the invention applied to the intake and exhaust lines of an internal combustion engine.

Similar reference characters designate corresponding parts throughout the several figures of the drawing.

10 Referring to the drawing, the intake manifold is designated as A and the exhaust manifold is designated as B, both communicating with the motor block in conventional manner. The intake manifold is provided with a starting unit designated generally as C and the main generator D is fitted in the exhaust line B as shown.

The starting generator C preferably includes a fitting attached to entrance of the intake manifold, said fitting comprising a tube 1 flanged at 20 its lower end and formed at its upper end with inner and outer walls 2 and 3 which provide a gas chamber 4. The upper end of the chamber 4 is closed by a cap 5 of ring like form to provide an intake opening 6. The chamber 4 communicates with the interior of the tube 1 by a plurality of jet pipes 7 whose inner ends are cut and disposed as indicated at 8 below opening 6 so that air entering the same will aspirate dry gas out of chamber 4 into the intake line. The throttle 30 valve T is located in the tube 1 as usual.

35 The outer wall 3 of the gas chamber 4 is embraced by an electrical heating unit including an annular casing 9 containing a heating coil E connected at its terminals 10 with a source of electrical supply. The casing 9 provides a gasifying chamber F which communicates at 11 with a raw liquid fuel inlet valve 12 which in turn communicates with the fuel pipe 13 leading to the main fuel supply valve 14. The heating gasifying

40 chamber F which contains raw fuel oil in its bottom portion is provided with a gas delivery tube 9^a extending down into the chamber 4 to conduct gas from the chamber in which the heating unit is enclosed into the chamber 4 so that 45 dry gas will freely pass into the chamber 4 and flow through tubes 7 into the air stream entering the intake pipe through opening 6.

The main fuel supply valve is connected by nipple 15 with a source of bulk fuel oil and 50 contains a passage 16 whose lower end is in communication at all times with starting fuel supply line 13. Above the inlet to line 13 the passage 16 is provided with a valve 17 for controlling the bulk supply of fuel oil to the coil 18 55 of the main generator D. This valve 17 is open, as shown, under normal running conditions, but

may be closed when the motor is to be stopped for any interval of time. When the valve 17 is open, the flow of oil to the lower end of conically wound spiral coil 18 may be manually regulated from passage 16 to the coil by valve 19.

The coil 18 of the main generator is located in the hollow central passage 20 of the generator formed by inner wall 21 through which the upper end of the coil enters at 22 to discharge fuel oil into the inner chamber 23 of the generator. The wall 21 is swedged at 21^a to divert part of the exhaust gases around the outside surface of the generator proper and is also provided with a plurality of openings 24 located beneath an annular downturned baffle 25 which openings communicate with an outer chamber 26. The space below these holes serves as a trap for fuel oil. As will be seen the top and bottom ends of the chambers 23 and 26 are closed by walls 27 and 28 and the chamber 26 is provided with an annular downturned baffle 29 lying below gasified fuel outlet connection 30.

It will also be seen that inner chamber 23 is provided at its upper wall 27 with a monoxide breather pipe 31 which opens into the exhaust line and when the motor is operating, will permit monoxide gas to be sucked into the inner gasifying chamber.

The parts forming the generator chambers 23 and 26 are surrounded by a casing 32 which houses the same completely and said casing being located in the exhaust line, it will be apparent that hot exhaust gases passing from the exhaust manifold B will internally and externally envelop the generator to provide heat for cracking the raw low grade fuel oil into a dry gas which is led from the generator chambers 23 and 26 by the tube 30 into the interior chamber of an elongated hollow gas volume control valve 33. This valve is formed by telescopically related tubular members and the inner rotatable part is provided with a V-shaped port 34 for controlling the outlet of tube 30 and a V-shaped port 35 controlling the inlet end of tube 36 communicating with chamber 4 of the starting generator C.

The gas volume control valve 33 is enclosed in a casing 34^a closed at one end and having an operators control shank and lever 34^b at its other end. This gas volume control valve may be manually adjusted to suit motor running conditions and therefore by properly adjusting fuel oil valve 19 and gas control valve 33, all working conditions over a desired range of operation may be finely and accurately adjusted or set. That is to say, the ports are circumferentially disposed and located at diametrically spaced points longitudinally of the tube. Rotating the part 33 by the control lever 34^b increases or reduces the gas passage areas at both the intake port 34 and outlet port 35. This provides an accurate control of the amount of gas delivered to the engine intake. In addition the chamber so formed becomes an accumulator providing a gas reserve to meet sudden acceleration from low to high speed in the few seconds required for throttle opening compensation by throttle controlled increase of fuel to the main generator.

The operation of the invention is as follows:

Assuming the valve 17 is set as shown, and the circuit to the terminals 10 is closed the heating unit E will glow and subject fuel oil supplied to chamber F by lines 11—12—13 to intense heat which will gasify the same, and, when the motor is turned over by an electric starter air entering opening 6 will aspirate gas through jets 7 from

chamber 4 which receives its supply of dry gas from said chamber F through tube 9^a, to form the initial combustible mixture for starting the motor under its usual ignition system.

Once the motor has started the exhaust flame passing through exhaust manifold B will gasify oil in the main generator and gas thus formed in chambers 23, 26 will pass through tube 30 into the chamber of the hollow valve 33 through port 34. The dry gas then passes through port 35 into pipe 36 which communicates with chamber 4. From this chamber the dry gas is aspirated through jets 7 into the intake air stream for sustained motor operation.

The starting heating unit E is provided with a suitable thermostatically controlled switch, not shown, which opens the circuit thereto when sustained motor operation takes place by gas supplied from the main generator. That is to say, cut-off is accomplished with a small standard type thermostat responding to the desired temperature development of the main generator so that when the latter is hot enough to produce sustained gasification the starting heating unit E is de-energized.

By way of further explaining the operation of the invention, it may be pointed out that initial gasification for starting purposes takes place in the chamber 4 in about forty-five seconds and the heating unit operation is electrically cut off when the main generator D has been sufficiently heated by exhaust gases, which usually requires another forty-five seconds. After the main generator reaches the desired temperature in approximately the aforesaid forty-five seconds the thermostat controlling the switch to the heating unit is opened and the starting unit then ceases to function, except that it will of course be understood that the chamber 4 continues to receive dry gas from the main generator.

By subjecting the coil 18 to the direct heat of exhaust flame, the fuel oil is cracked therein so that gas entering from the upper end of the coil into the chamber 23 of the main generator will be in what may be termed a semi-dry condition.

The gas from chamber 23 passes through opening 24, and the downturned baffle 25 retards the flow of almost totally dry gas as it passes into the outer chamber 26 where it is completely dehydrated before encountering the baffle 29 to pass through the fuel outlet connection 30. As previously indicated the lower end of chamber 23 will trap any possible semi-liquid fuel and hold it there until it too cracks into gas. The downturned or conical baffle 25 above the openings 24 acts as a hood and forces the gas over to and against the hot surface of the inner wall of chamber 26. Both baffles 25 and 29 are at cracking temperature, delaying and partially trapping the gas and thus completing the drying-out stage.

A slotted, rotatable valve, which is connected by adjustable linkage with the engine air-supply throttle provides for variable speeds from low to high, and the throttle T, and a conventional valve hook-up (not shown) properly and automatically relates the amount of fuel fed to the main generator directly to the amount of air fed to the engine, thus providing the correct amount of gas supply for all desired speeds.

I claim:

1. A gasifying carburetor for use on the intake and exhaust manifolds of internal combustion engines, comprising, a starting gasifying unit communicating with the intake manifold, a main

generator located in the path of discharge of exhaust gases in the exhaust manifold, means for establishing communication between the main generator and the starting gasifying unit, said means including a gas volume control valve serving as an accumulator to meet differential acceleration speeds, and means for supplying the main and starting generator with liquid fuel.

2. A gasifying carburetor for use on the intake and exhaust manifolds of internal combustion engines, comprising, a starting gasifying unit communicating with the intake manifold, a main gas generator in the exhaust manifold, means for conducting gas from the main generator to the starting gasifying unit, and a carbon monoxide breather tube having its inlet end disposed in the exhaust stream of the exhaust manifold and having its outlet end communicating with the main generator, and means for supplying fuel oil to the main and starting generator units.

3. A gasifying carburetor for use on the intake and exhaust manifolds of internal combustion engines, comprising, a starting gasifying unit having means communicating with the intake manifold, valved fuel oil supply means for starting gasifying unit, a main gas generator in the exhaust manifold line, means for conducting gas from the main generator to the starting gasifying unit, said main gas generator comprising a housing fitted to the exhaust line, a generator proper within the housing and including a central passage formed by a wall whose lower end is swaged inwardly, a spiral coil in the said central passage of the generator proper and having one end communicating with a source of fuel oil supply, means forming inner and outer gasifying chambers, said inner chamber receiving discharge from the upper end of said coil, means for establishing communication between said inner and outer chambers, hood-like baffle means disposed over said last mentioned means, other baffle means in the outer chamber anterior to the means for conducting drying gas from the main generator to the starting gasifying unit, and valved means for supplying fuel oil to the main generator unit.

4. A gasifying carburetor for use on the intake and exhaust manifolds of internal combustion engines, comprising, a starting gasifying unit communicating with the intake manifold and including means forming an intake passage and a surrounding dry gas chamber, aspirating jets leading from said gas chamber into the intake passage, an electrical heating unit surrounding said gas chamber, a casing housing said heating unit, a fuel oil inlet for said casing, a gas delivery tube for the casing and in discharging relation to said dry gas chamber, and a main gas generator in the exhaust manifold line, and means establishing communication between the main gas generator and the dry gas chamber of the starting unit for sustained motor operation.

5. A gasifying carburetor for use on the intake and exhaust manifolds of internal combustion engines, comprising, a starting gasifying unit communicating with the intake manifold and including means forming an intake passage and a surrounding dry gas chamber, aspirating jets leading from said gas chamber into the intake passage, an electrical heating unit surrounding said gas chamber, a casing housing said heating unit, a fuel oil inlet for said casing, a gas delivery tube for the casing and in discharging relation to said dry gas chamber, and a main gas generator in the exhaust manifold line, and means establishing communication between the main gas generator and the dry gas chamber of the starting unit for sustained motor operation, said means including a gas volume control valve having a hollow cylindrical stem provided with longitudinally spaced ports controlling gas flow upon manual rotary adjustment from a gas tube leading from the main generator to a gas tube leading to the dry gas chamber of the said starting unit.

6. A gasifying carburetor for use on the intake and exhaust manifolds of internal combustion engines, comprising, a starting gasifying unit communicating with the intake manifold and including, a dry gas chamber, an electrically heated starting fuel oil gasifying chamber having connection with a fuel oil supply, a gas delivery tube leading from the starting gasifying chamber to the dry gas chamber, a main generator in the exhaust manifold line, a gas volume control valve for regulating gas volume between the main generator and the dry gas chamber of the said dry gas chamber, said main generator including, a housing concentric with the exhaust line, a generator having concentric wall means forming a central exhaust gas opening and inner and outer gasifying chambers, the wall means between said last mentioned chambers having openings, a dry gas tube leading from the outer dry gas chamber to the gas volume control valve, a breather tube establishing communication between the exhaust passage and the inner chamber, a fuel oil coil communicating at its upper end with the upper portion of the inner gasifying chamber and located in the central exhaust gas passage of the generator, and control valve means between the lower end of the coil and a source of fuel supply.
